UNITED STATES PATENT OFFICE.

CLIFFTON R. SCUDDER, OF ST. LOUIS, MISSOURI, AND JAMES B. HUGUELET, OF CHICAGO, ILLINOIS, ASSIGNEES TO SAMUEL CUPPLES ENVELOPE COMPANY, OF CHICAGO, ILLINOIS, A CORPORATION OF MISSOURI.

DISK-FEEDING MECHANISM FOR EYELETING MACHINES.

1,405,015.

Specification of Letters Patent. Patented Jan. 31, 1922.

Original application filed July 19, 1920, Serial No. 397,242. Divided and this application filed May 16, 1921. Serial No. 469,821.

To all whom it may concern:

Be it known that we, CLIFFTON R. SCUDDER and JAMES B. HUGUELET, citizens of the United States of America, and residents of St. Louis, Missouri, and Chicago, Cook County, Illinois, respectively, have invented a certain new and useful Improvement in Disk-Feeding Mechanism for Eyeleting Machines, of which the following is a specification.

Our invention relates to a machine for affixing fastenings to envelopes, and particularly to that type of machine in which the seal flap and body of the envelope are provided with a circular washer or disk attached thereto by eyelets to one of which a closing cord or string is attached with the free end adapted to be wound successively around the two eyelets and beneath the washers thereby securely uniting the seal flap and body of the envelope.

This application is a division of our application for machines for affixing fastenings to envelopes, Serial No. 397,242, filed July 19, 1920, and the particular feature claimed in this application relates to the improved means for feeding the circular disks or washers into proper position to be attached to the body portion of the envelope.

The features and objects of our invention will be more readily understood by having reference to the accompanying drawings in which we have illustrated one embodiment of our invention.

Figure 1 is an elevation of a machine embodying the features of our invention looking at one side thereof.

Fig. 2 is a similar view, looking at the opposite side thereof.

Fig. 3 is an enlarged front elevation of a portion of the machine.

Figs. 4 and 5 are detail plan views of the slide for feeding the lower washer or disk, showing this slide in different operative positions.

Fig. 6 is a sectional view taken on the line 6—6 of Fig. 5.

Fig. 7 is a sectional view taken on the line 7—7 of Fig. 6.

Fig. 8 is a detail view of one of the disks or washers.

Fig. 9 is a view of an envelope after the

attaching means have been secured thereto by the machine.

Our machine consists essentially of an upright frame 20 having a forwardly extending supporting bed 21 which is formed with a pointed nose adapted to be inserted within the envelope 22 to which the fastening means are to be secured. As shown in Fig. 1, when the envelope is in position, the seal flap is supported by the upper surface of the supporting bed while the forward edge of the body of the envelope is adjacent the lower surface of the projecting nose of this supporting bed. Co-operating with the upper surface of the supporting bed there is suitable mechanism including a punch, eyelet feed, disk and string feeding mechanism for feeding and securing to the seal flap of the envelope the disk and string attaching means. There is also associated with this mechanism, means for feeding and securing a reinforcing washer to the opposite surface of the seal flap.

Co-operating with the lower face of the projecting nose of the supporting bed 21, there is a plunger and eyelet, disk, and reinforcing washer feeding means, somewhat similar to those co-operating with the upper die except that the mechanism co-operating with the lower die has been modified and changed somewhat in order to enable the same to operate upwardly against the lower surface of the supporting bed as contra-distinguished from the first mechanism which operates downwardly against the upper surface of the supporting bed.

The mechanism shown in association with the upper anvil is of itself no part of our present invention, except in so far as this upper operating mechanism co-operates with the mechanism associated with the lower anvil in making a machine which operates to simultaneously and by one operation apply the fastening means to both the seal flap and the body of the envelope.

The power for driving the entire mechanism is derived from a driving pulley 25, which is connected to the shaft 26 through a suitable one revolution clutch mechanism 27 indicated diagrammatically, which clutch can be of any well known type and is controlled by the foot-pedal 28 so that upon op-

erating the same the shaft 28 is caused to make one complete revolution, all in the manner well understood in connection with the operation of machines of this character.

5 The mechanism for applying the fastening means to the body of the envelope and which co-operates with the under face of the supporting bed, with which mechanism our invention is chiefly concerned, consists as 10 heretofore stated of elements somewhat similar to those employed in connection with the mechanism co-operating with the upper anvil. There is provided a reciprocating plunger 57 which carries a spring-pressed pin 58, which plunger is adapted to be reciprocated through the medium of the crank 59 and connecting links 60—61. A stack of washers or disks 62 are mounted upon a rod 63, but instead of being fed by gravity, 20 as in the case of the upper washers, it is necessary to provide a positive means for feeding these disks upwardly on this rod. This is accomplished by means of a carriage 64 which engages the lowermost disks and is forced upwardly by power derived from the weight 65 which is connected to this carriage through the medium of a rope 66. In this manner there is a constant upward pressure on the disks so that the upper disk is 30 forced into position to be engaged by the reciprocating slide 67. (See Fig. 6.). This slide is provided with a shoulder 68 so that as the slide is reciprocated it engages with the top washer and feeds the same laterally 35 off the top of the stack. This slide is adapted to be reciprocated by the operation of the cam 39 mounted on the shaft 26 and rocking arm 41 to the outer end of which the arm 69 is secured, the upper end of this arm being secured to a crank 70 on one end of a 40 shaft 71. To the opposite end of this shaft a crank 72 is connected, the opposite end of which is connected to the depending lug 73 on the slide 67. This construction is such 45 that as the cam 39 rotates, the slide 67 is reciprocated so as to feed the upper disk or washer in the stack 62 forwardly into a position to be engaged by the spring pin 58 in the end of the reciprocating plunger 57. In 50 order to properly support the washer when it is thus fed off the top of the stack, it is necessary to provide special supporting means such as are shown in detail in Figs. 4 through 7. This consists essentially of a 55 supporting member 74 mounted upon the slide 67, which supporting member is provided with a forwardly extending portion 75 having a pair of downwardly curved supporting arms 76 which are in a position to receive and hold the washer. The end of the 60 supporting member 74 is cut away at 77 to permit the yielding pin 58 to engage with a washer supported by the slide. This supporting slide 74 is connected to the main 65 slide 67 by a spring connection 78 and the

main slide 67 is provided with an upwardly projecting portion 79 which, upon the forward movement of the slide 67, is adapted to engage the forward end of the supporting slide 74 and force the same outwardly into the position shown in Fig. 4. That is, in operation the slide is normally in the position shown in Figs. 5 and 6, but as the slide 67 is forced outwardly it picks the disk off the top of the stack and moves the same on to the supporting arms 76 and then the slide 67 and supporting member 74 move together until this disk is carried into a position immediately over the spring-pressed pin 58. Then as this pin moves upwardly, the washer 80 is slipped over the end of the pin and then the slide 67 is retracted and the spring 78 pulls the supporting member 74 backwardly so that this supporting member is moved out of the path of the reciprocating plunger 57. 85 The eyelets for the lower fastening means are supplied from a suitable hopper 80 down the eyelet-chute 81, which eyelet chute is carried by a sliding member 82 which is adapted to be reciprocated through the medium of the link 83, the opposite end of which is connected to the arm 84, upon one end of a stud shaft 85, which shaft is reciprocated through the medium of the connections 59 and 60 in the manner hereinbefore described. In this way this eyelet-chute is moved in and out of the path of the plunger 57.

It will thus be seen that we have devised a very efficient means for feeding the circular disk or washer into position to be secured to the body portion of the envelope, and while we have described one specific embodiment of our invention, it will be understood that we do not wish to be limited to the exact construction shown and described, but that various changes and modifications may be made without departing from the spirit and intent of our invention.

What we claim as our invention is:

1. In a machine of the class described, a supporting bed, a reciprocating plunger for co-operating with said bed, a stack of disks mounted adjacent said plunger, means for moving a circular disk or washer from the top of said stack into the path of said plunger, said means including a reciprocating slide, a shoulder on said slide for engaging with the top disk of said stack, means for reciprocating said slide to thereby move said top disk off of said stack into a position to be engaged by said plunger, and supporting fingers for engaging beneath said disk when moved laterally to hold the same in position above the plunger.

2. In a machine of the class described, a supporting bed, a reciprocating plunger for co-operating with said bed, a stack of disks mounted adjacent said plunger, means for moving a circular disk or washer from the

- top of said stack into the path of said plunger, said means including a reciprocating slide, a shoulder on said slide for engaging with the top disk of said stack, 5 means for reciprocating said slide to thereby move said top disk off of said stack into a position to be engaged by said plunger, supporting fingers for engaging beneath said disk when moved laterally to hold the 10 same in position above the plunger, and means for retracting said supporting fingers when said plunger moves upwardly to engage said disk.
3. In a machine of the class described, a 15 supporting bed, a reciprocating plunger for co-operating with said bed, a stack of disks mounted adjacent said plunger, means for moving a circular disk or washer from the top of said stack into the path of said 20 plunger, said means including a reciprocating slide, a shoulder on said slide for engaging with the top disk of said stack, means for reciprocating said slide to thereby move said top disk off of said stack into 25 a position to be engaged by said plunger,
- supporting fingers yieldingly connected with said slide for engaging beneath the disk or washer when the same is moved laterally to support the same above said plunger, and means for retracting said supporting fingers 30 when the plunger is moved upwardly to engage said disk.
4. In a machine of the class described, a supporting bed for engaging with an envelope, a stack of circular disks or washers 35 supported below said bed, a reciprocating slide for engaging with the top washer of said stack and moving the same laterally from said stack, a reciprocating plunger adapted to engage said top disk or washer 40 when moved laterally for carrying the same upwardly against said supporting bed, and eyelet-setting means for securing said disk or washer to the envelope.
